R. J. Gallieath
ATTORNEY.

UNITED STATES PATENT OFFICE.

CLINTON HAYS AND WELLINGTON M. THOMAS, OF DENVER, COLORADO.

VALVE-SPRING COMPRESSOR.

Application filed August 31, 1925. Serial No. 53,505.

This invention relates to a device for lifting the valve spring of an internal combustion engine to facilitate the removal of the valve, and has for its principal object the provision of a device of this character which will be economical to manufacture, efficient in operation and which will contain adjustments by means of which it may be readily adapted to various types and sizes of engines.

Another object of the invention is to provide a device of this character in which, when desired, an increased leverage may be obtained without it being necessary to build the device of an awkward length.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:

Fig. 1 is a side elevation of the device as it appears when first applied beneath an engine valve.

Fig. 2 is a similar view, partly in section, with the device locked in the raised position.

Fig. 3 is a perspective view of the device.

Fig. 4 is a detail view of the spring cup employed in the device.

Fig. 5 is a detail view of an alternate form of the spring cup.

Devices have been manufactured some-
what along the lines of the present invention, but these devices were applicable to only a single type of engine so that a repair shop was required to carry a number of different devices so as to be prepared for any type of engine. The present invention, however, is designed so that it may be employed with any of the usual types and sizes of engines.

The invention comprises an inverted U-shaped fulcrum 10 in which a U-shaped lever arm 11 is supported. Each extremity of the lever arm 11 is pivotally secured to a spring cup 12. Slidably mounted at the opposite end of the lever 11 is a U-shaped extension 13. Removal of the extension 13 is prevented by means of a pin 14 carried by

the lever 11 which travels in a slot 15 formed in the extension 13. The extension 13 is provided with hooked-shaped projections 16 which engage the lever 11 and co-act with the pin 14 to maintain the extension in alignment with the lever. Normally, the extension occupies the position of Fig. 1, but when the device is being used to lift an unusually stiff valve spring, it is drawn out of the position of Fig. 1 to that of Fig. 2 and acts to increase the leverage of the device.

In operation, the fulcrum 10 is rested upon the cylinder casting 17 of the engine, an arcuate indentation 27 being formed in the fulcrum to surround the valve guide 18 thereof. The spring cup 12 is slipped under the valve spring, illustrated at 19, there being a slot 20 in its bottom for the reception of the valve stem, illustrated at 21. The device is now in the position of Fig. 1.

By depressing the free extremity of the lever 11, to the position of Fig. 2, the valve spring will be compressed as illustrated in that view. This allows free access to the valve spring pin, 22, so that the valve, illustrated at 23, may be readily removed.

In different types of engines, the valve guides 18 are of different length so that the resting place of the fulcrum will be at different heights from the lower extremity of the valve spring 19. To adapt the device to these various conditions, I form a series of pivot rests 24 in the fulcrum 10 adapted to receive the pivot pin 25 of the lever 11. This allows ready adjustment of the device to suit various heights of valve guides. In adjusting the device, it is placed in the position of Fig. 1, the fulcrum 10 is then held with one hand and the lever 11 in the other hand, until the pivot pin 25 rests in the pivot rest 24 of the proper height. The lever 11 is then depressed and the spring compressed. With this arrangement, it is not necessary to perform any extra operations in adjusting the device since the adjustment is made simultaneously with the operation thereof.

To accommodate valve springs of various diameters, I form the valve cup in two similar sections, 29 and 30. Each section being carried upon one of the extremities of the lever 11. The lever 11 is of spring material and its elasticity serves to maintain the two sections 29 and 30 normally together. They may be spread apart however, when desired, to accommodate a valve spring of

relatively large diameter. The fulcrum 10 is also of spring material so that it will maintain itself snugly against the lever 11. By forming these parts of spring material, they readily accommodate themselves to differing diameters of spring. For the convenience of the operator, a hand rest 28 is carried on the extension 13.

The natural elasticity of the lever 11 is sufficient under ordinary conditions to maintain the two parts of the spring cup 12 against the spring 19 when it is being raised. If additional security is desired, however, lugs 31 and 32 are formed upon the parts 29 and 30 respectively, to carry an adjusting screw 33 which may be employed to maintain the two parts of the spring cup at the desired separation.

While a specific form of the improvement has been described and illustrated herein, it is desired to be understood that the same may be varied, within the scope of the appended claims, without departing from the spirit of the invention.

Having thus described the invention, what we claim and desire secured by Letters Patent is:—

1. A valve spring compressor comprising two semi-cylindrical cups adapted to engage opposite sides of a valve spring; a bottom in each of said cups adapted to engage the bottom of a valve spring; a U-shaped lever

pivoted at one of its extremities to one of said cups and at its other extremity to the other of said cups; a U-shaped extension adapted to partially surround and slide on said lever; and a U-shaped fulcrum for said lever.

2. A valve spring compressor comprising a lever, a piece of sheet metal bent to partially surround said lever; and a hand rest formed on said sheet metal, said sheet metal being slidable on said lever to form an extension thereof.

3. A valve spring compressor comprising two semi-cylindrical cups adapted to engage opposite sides of a valve spring; a bottom in each of said cups adapted to engage the bottom of a valve spring; a U-shaped lever pivoted at one of its extremities to one of said cups and at its other extremity to the other of said cups; a U-shaped extension adapted to partially surround and slide on said lever; a U-shaped fulcrum for said lever having a longitudinal vertical slot in each of its arms with projections along one side of each of said slots; and pivot pins in said lever adapted to engage said projections.

In testimony whereof, we affix our signatures.

CLINTON HAYS.
WELLINGTON M. THOMAS.
